MAGNETIC CONTOURING SYSTEM

Wilson M. Powell, Berkeley, Calif., assignor to the
United States of America as represented by the
United States Atomic Energy Commission

Application September 10, 1948, Serial No. 48,747

16 Claims. (Cl. 175—183)

1

My invention relates to a magnetic graphing method and device and, in particular, to an arrangement for contouring the intensity of a magnetic field about the exposed face of a magnetic pole piece.

The primary object of this invention is to provide a simple arrangement for contouring the intensity of a magnetic field.

Another object of this invention is to provide a method of marking on a paper overlay all points of an equal predetermined flux intensity of a magnetic pole.

A further object of this invention is to provide a simple, accurate, and economical method of plotting the magnetic field intensity of a magnetic field.

Other objects and advantages of my invention will be apparent from a further study of the following specification, claims, and drawings. For a better understanding of my invention, therefore, reference is made in the following description to the accompanying drawings, in which:

Figure 1 is an assembly view, partly diagrammatic and partly perspective illustrating a preferred embodiment of my invention;

Fig. 2 is a vertical sectional view of the search coil and supporting tube taken axially of the latter (Fig. 1);

Fig. 3 is a plan view of the collimating lens 19 shown in Fig. 1;

Fig. 4 is a sectional view of the collimating lens of Fig. 3 taken on line 4—4 of the latter;

Fig. 5 is a typical pattern obtained with my invention from a rectangular magnetic pole piece such as is shown in Fig. 6; and

Fig. 6 is a perspective view of an electromagnet of which a flux density contour is desired.

Reference is now made to Fig. 1 diagrammatically showing my magnetic contouring system in which a preferably cylindrical search coil 1 is mounted on and frictionally supported by a vertical nonmagnetic support tube 2 threaded into an electrically insulating and nonmagnetic search base 3 which may be composed of an insulator such as polystyrene. Search coil 1 may be supported at any desired height on support tube 2 by means of a phosphor-bronze spring 44 (Fig. 2) silver soldered to the inside of a nonmagnetic coil base 45 so as to bear against the wall of support tube 2, thereby frictionally supporting the search coil. Coil 1 is preferably formed of about two thousand turns of number 42 wire wound on base 45 so as to give an effective coil area of approximately twenty thousand square centimeters. The search base 3 is sep-

arated from direct contact with the face of a magnetic pole piece 7 to be probed through the utilization of a paper contour sheet 8 of relatively thin stock (a satisfactory thickness having been found to be .002 inches in thickness) entirely covering such face. In series with and identical to the search coil 1 but connected in opposition thereto, is a stationary compensating coil 9 which is placed in the measurable magnetic field to compensate for any overall change in magnetic flux density. In practice, the compensating coil 9 is placed in a convenient location on sheet 8 out of the way of the course of the search coil 1. When probing of the area beneath the compensating coil 9 is desired the latter is then moved to a new location on the sheet.

When the search base is moved through the magnetic field of magnetic pole piece 7, the change in magnetic flux induces a voltage in the search coil 1 which is carried by wires 6 to a galvanometer 10. A central suspension 13, such as the customary elongated filament of the galvanometer 10, is mounted so as to permit rotation about its central axis and is of a type in which there is substantially no restoring torque tending to return to its neutral position a plane mirror 14 mounted on the suspension 13. I have found that a D'Arsonval galvanometer with the restoring-torque spring removed or a galvanometer for which the restoring torque is compensated, such as in Patent No. 2,356,608 issued to Lorin O'Bryan, will operate satisfactorily.

To one side of the galvanometer 10 is provided a light beam source 15 containing a lamp 16, preferably of the point source type, a convex collimating lens 19, and a convex focusing lens 20. The convex collimating lens 19 (shown in Figs. 3 and 4) is covered on one side with a mask 21 in which there are two diametrically and vertically aligned apertures 22 and 25; the first mentioned and upper aperture being circular and provided with a vertically centered cross-hair 26, and the lower aperture 25 being in the form of an elongated rectangle whose longer sides are symmetrically disposed with respect to the diameter including cross-hair 26. Collimating lens 19 serves to collimate the light of lamp 16 into two vertically aligned beams having the shape of apertures 22 and 25; such beams then pass through convex lens 20 which focuses the beams upon galvanometer mirror 14.

Disposed to one side of the mirror 14 is an elongated scale 27 divided in millimeters and curved about the filament 13 as a center at a convenient radial distance therefrom. Slidably

carried along a slot 29 disposed longitudinally and spaced from the bottom of scale 27 in the plane formed by the light source 15, the mirror 14, and the scale 27 and thus being in the path of the lower portion of the beam reflected from mirror 14, is a photo-electric cell unit 28 which may be secured in an adjusted position along slot 29 by a support arm 36 attached to photo-cell 28 and a thumb-screw 31 adapted to fit slot 29. The degree of rotary motion of mirror 14 is indicative of the extent of any magnetic flux change, and the reflection of the upper beam of light source 15 from mirror 14 on scale 27 provides a direct measure of such change. Photo-electric cell unit 28 is provided with an opaque hood 24 having a single opening as rectangular aperture 32 identical with that of aperture 25 of collimating lens 19 for the admission of the lower rectangular beam of light reflected from mirror 14. Aperture 32 in photo-electric cell 28 is identical with aperture 25 in order that photo-electric cell 28 will be activated only when the reflected lower beam falls directly into aperture 32, a deviation of only one millimeter of the lower rectangular beam from aperture 32 being sufficient to prevent energization of photo-electric cell 28.

A voltage generated by the light sensitive surface of photo-electric cell 28 when the lower rectangular beam reflected from mirror 14 penetrates the rectangular orifice 32 and actives the photo-sensitive surface of cell 28 is applied to a voltage amplifier 33 disposed near the photo-electric cell 28 through conductors 35. Voltage amplifier 33 is of the direct-coupled type for direct current amplification, and satisfactory operation may be obtained with the direct-coupled amplifier shown in Fig. 15c, page 376, of the Radio Engineers' Handbook by Frederick Emmons Terman, 1943 edition. The output of amplifier 33 operates a relay (of which only the contacts 34 are shown) for closing the primary circuit 37 of an adjacent transformer 38. The ratio of transformation of transformer 38 is about 100 to 1 in order that the primary power line voltage of 115 volts A. C. will be converted in a secondary winding 39, one end of which is grounded, to at least 10,000 volts. Satisfactory operation has also been obtained by using a step-down transformer for reducing the power line voltage to approximately six volts and applying this low voltage to the primary of a Ford spark coil, the output of which is also about 10,000 volts.

The output of the transformer secondary winding 39 is led, by means of an insulated high voltage cable 40, into the search base 3. The cable 40 enters base 3 through the center of one of the sides and parallel to the bottom of the base, then turns downward to a 90-degree angle directly under the support tube 2, terminating and barely breaking through the bottom surface of the base at a point 43. Cable 40 is stripped of insulation for approximately one-half inch back of point 43 in order that no insulation will interfere with the exposure of the bare wire at point 43. Photo-electric cell amplifier 33 operates to energize the relay associated with contacts 34 and thereby permits power to be applied to the primary 37 of transformer 38. The high voltage induced in the secondary winding 39 and transmitted along cable 40 to point 43 is sufficient to permit a spark to arc from point 43 to the grounded magnetic pole piece 7 puncturing a small hole in the paper contour sheet 8.

In operating my magnetic contouring system, a control handle 46 articulately attached to the base assembly 3 by a hinge 49 is used to horizontally sweep the search coil 1 across the magnetic flux field which is perpendicular to the surface of magnet pole piece 7. As the search coil 1 passes through variations in flux intensity, a varying voltage is induced in search coil 1 which is applied to galvanometer 10. The flux changes encountered by search coil 1 are integrated by galvanometer 10 and appear as incremental voltage increases whenever coil 1 passes through magnetic flux of increasing intensity and incremental decreases whenever coil 1 passes through flux of decreasing intensity. The varying voltage applied to galvanometer 10 effects a rotary motion of mirror 14 causing the beam of light of lamp 16 to traverse scale 27 in accordance with the flux variations. Photo-electric cell 28 is adjusted along scale 27 at a preselected position corresponding to a desired flux intensity and is, therefore, activated whenever the lower beam of light formed by aperture 25 falls on aperture 32. Thus, whenever a preselected magnetic flux intensity is encountered by search coil 1 during the traverse of the pole piece 7, mirror 14 of galvanometer 10 reflects a beam of light onto photo-electric cell 28 generating a voltage in the photo-cell which is transmitted to voltage amplifier 33. The contacts 34 associated with amplifier 33 remain closed during the generation of the photo-cell voltage permitting transformer 38 to be energized and an arc to be formed between point 43 and pole piece 7 through paper sheet 8. A series of small holes is punctured in paper sheet 8 whenever search coil 1 is probed into an area of preselected flux intensity. By altering the position of photo-cell 28 along scale 27, the system will respond to some other value of flux density. The small punctures in contour sheet 8 corresponding to each particular scale setting are connected to give a series of lines of constant vertical magnetic field intensity. Since the flux value of each contour line is known, it is merely a matter of simple interpolation to determine the flux at any point between successive contour lines. If desired, search coil 1 may be moved vertically along support rod 2 so as to permit comparisons to be made of the distribution of the magnetic field at different distances from the face of the magnetic pole piece.

Fig. 5 illustrates magnetic contour lines 50 of a typical flux pattern on the contour sheet 8 as might be derived from a flux field probe with my contouring system on pole face 7 of an electromagnet 51 having a closed external core 52 and separate pole windings 55 (Fig. 6). The lines 50 are spaced widely apart near the center of contour sheet 8 where the flux is relatively uniform and closely spaced near the edges where the leakage flux effects relatively abrupt changes in perimetal flux density. By means of adequate magnetic shimming, then subsequent replotted of the flux density contour lines, any desired flux density pattern may be obtained.

While I have described the salient features of this invention with respect to one embodiment, it will, of course, be apparent that numerous modifications may be made within the spirit and scope of this invention. It is possible, with suitable detecting means, for this invention to make contour plots of electrostatic, radiant energy, heat, or any other vectorial field of variable intensity. For example, an electrostatic meter mounted on base 3 could provide a suitable voltage to activate the recording system as well as the dis-

closed magnetic flux coil. Also, for radiant energy fields, a small coil coupled to a crystal rectifier could be used to search a field of radiant energy and give an output voltage proportional to the radiant field intensity; likewise, a thermocouple mounted on base 3 could be used to produce a voltage proportional to a field of variable heat intensity. These varying voltages could be coupled to the galvanometer 10, and the recording action would be as described herein. I do not, therefore, desire to limit the invention to the exact details shown except insofar as they may be defined in the following claims.

What is claimed is:

1. A method of contouring the flux intensity emanating from a magnetic surface which comprises ascertaining continuously the flux intensity at contiguous points in a plane spaced from said surface and simultaneously perforating a thin record surface disposed between said plane and said magnetic surface in accordance with such points of equal flux density as are encountered.

2. A method of contouring the flux intensity emanating from a magnetic surface which comprises ascertaining the flux intensity of said magnetic surface at contiguous points in a plane spaced from said surface and simultaneously causing an electric arc to pierce a thin record surface placed on said magnetic surface whenever the magnetic flux reaches some predetermined value.

3. A vectorial field testing device comprising a probe, a field intensity detector carried by said probe, a marking device adapted to record data upon a recording sheet disposed in said vectorial field, and means controlled by said field intensity detector for operating said device whenever the strength of the field attains a predetermined value.

4. A magnetic field testing device comprising a probe, a field intensity detector and a marking device adapted to record data upon a recording sheet disposed in said magnetic field, said device being carried by said probe, and means controlled by said field intensity detector for operating said device whenever the strength of the field attains a predetermined value.

5. An apparatus for plotting the contour of a magnetic field comprising an element responsive to the flux density of said magnetic field, means whereby said magnetic-responsive element may be moved through said magnetic field, a recording element adapted to be moved along a path within said magnetic field corresponding to the path traversed by said magnetic-responsive element, and means responsive to said magnetic-responsive element for actuating said recording element.

6. A magnetic field testing device comprising a probe adapted to be moved over a recording sheet disposed on the inhomogeneous magnetic surface of a magnet, a search coil carried by said probe, a flux integrating meter associated with said search coil, a circuit terminal carried by said probe adjacent said recording sheet, means controlled by the net change in magnetic flux through said flux integrating meter as said probe is progressively moved back and forth across said recording sheet for producing a spark at said terminal each time the net change in magnetic flux attains a predetermined value, whereby a series of marks is made on said recording sheet along lines indicative of the magnetic flux distribution.

7. In combination with a magnet pole face having a non-uniform magnetic field therethrough, a testing apparatus receiving impulses from said magnetic field and imposing said impulses upon a galvanometer including a mirror, a light source including a light-transmitting aperture, a photo-sensitive element having a relay associated therewith, a high voltage spark-producing means operated by said relay and means including said mirror for focusing the image of said aperture on said photo-sensitive element at a predetermined mirror position whereby said relay actuates said spark-producing means.

8. Means for plotting magnetic field intensities and comprising in combination, a magnet pole face, means establishing a non-uniform magnetic field therethrough, a surface upon which the relative intensities of said field are to be plotted, means for applying a mark upon said surface corresponding in location and field intensity value to that position within the field and that relative field intensity at which a reading is simultaneously being taken, a probe adapted to be moved through said field, galvanometer means connected to said probe and adapted to be moved to a position corresponding to the relative field intensity encountered by said probe, and an adjustably calibrated control means for actuating said marking means, said control means being actuated only when the position assumed by said galvanometer means corresponds to the calibrated position of said control means.

9. Apparatus as defined in claim 8 wherein said surface includes a recording sheet disposed on the magnet pole face.

10. Apparatus as defined in claim 8 wherein said means for applying a mark includes a spark-producing means.

11. Apparatus as defined in claim 8 wherein said control means includes a photo-sensitive element actuated by light reflected from a mirror carried by said galvanometer.

12. A method of contouring the flux intensity at various levels above a magnetic surface which comprises ascertaining the flux intensity at contiguous points in a plane spaced from said surface and simultaneously spark-perforating a thin record surface directly beneath said points whenever the magnetic flux reaches some predetermined value, and repeating the said ascertaining and recording steps in planes variously spaced from said surface to provide a depth-varying magnetic contouring record of the field emanating from said magnetic surface.

13. A magnetic field testing device comprising an element responsive to the flux density of said magnetic field, means movable across said magnetic field and serving also to support said element at adjustable positions in the direction of said field, a recording element carried by said means, and means responsive to said element for actuating said recording element.

14. Apparatus as defined in claim 13 including a second element responsive to the flux density of said magnetic field and connected in series opposition to said first element to compensate for overall changes in magnetic flux density.

15. A magnetic field testing device comprising a search coil, means movable across said magnetic field and serving to support said element in general axial coincidence with the direction of said field, a recording element carried by said supporting means and disposed on the axis of

said search coil and means responsive to said element for actuating said recording element.

16. Apparatus as defined in claim 15 wherein said recording element comprises a spark producing means, and a spark-perforable recording sheet disposed in a plane extending generally normal to the direction of said field.
